CLAIM

The ornamental design for a capsule, as shown and described.

DESCRIPTION

FIG. 1 is a perspective view of embodiment one of a capsule, showing our new design;

FIG. 2 is a partially enlarged view thereof, taken from FIG. 1;

FIG. 3 is a side view thereof;

FIG. 4 is a cross-section view thereof, taken along line 4-4 in FIG. 3;

FIG. 5 is a partially enlarged view thereof, taken from FIG. 4;

FIG. 6 is a bottom view thereof;

FIG. 7 is a perspective view of embodiment two of a capsule, showing our new design;

FIG. 8 is a partially enlarged view thereof, taken from FIG. 7;

FIG. 9 is a side view thereof;

FIG. 10 is a cross-section view thereof, taken along line 10-10 in FIG. 9;

FIG. 11 is a partially enlarged view thereof, taken from FIG. 10;

FIG. 12 is a bottom view thereof;

FIG. 13 is a perspective view of embodiment three of a capsule, showing our new design;

FIG. 14 is a partially enlarged view thereof, taken from FIG. 13;

FIG. 15 is a side view thereof;

(Continued)

FIG. 16 is a cross-section view thereof, taken along line 16-16 in FIG. 15;
 FIG. 17 is a partially enlarged view thereof, taken from FIG. 16;
 FIG. 18 is a bottom view thereof;
 FIG. 19 is a perspective view of embodiment four of a capsule, showing our new design;
 FIG. 20 is a partially enlarged view thereof, taken from FIG. 19;
 FIG. 21 is a side view thereof;
 FIG. 22 is a cross-section view thereof, taken along line 22-22 in FIG. 21;
 FIG. 23 is a partially enlarged view thereof, taken from FIG. 22;
 FIG. 24 is a bottom view thereof;
 FIG. 25 is a perspective view of embodiment five of a capsule, showing our new design;
 FIG. 26 is a partially enlarged view thereof, taken from FIG. 25;
 FIG. 27 is a side view thereof;
 FIG. 28 is a cross-section view thereof, taken along line 28-28 in FIG. 27;
 FIG. 29 is a partially enlarged view thereof, taken from FIG. 28; and,
 FIG. 30 is a bottom view thereof.
 The dot-dash broken lines are included to show partially enlarged views only and form no part of the claimed design.
